H. G. BARRETT

SHAFT FOR GOLF CLUBS AND THE LIKE

Filed March 22, 1926

UNITED STATES PATENT OFFICE.

HAROLD G. BARRETT, OF WILMETTE, ILLINOIS, ASSIGNOR TO PYRATONE PRODUCTS CORPORATION, OF CHICAGO, ILLINOIS, A CORPORATION OF ILLINOIS.

SHAFT FOR GOLF CLUBS AND THE LIKE.

Application filed March 22, 1926. Serial No. 96,368.

This invention relates in general to golf clubs but more specifically to the shaft employed in connection therewith, and one of the objects of the invention is to provide an improved cover or casing for the shaft which is adapted to be telescoped or sleeved over the shaft or core and the two bound together by a wedging operation, thereby rendering it possible to produce the casing as a separate 10 and complete article of manufacture which may be sold as such to be applied to a shaft or core.

Such a casing may be applied without the services of an expert, and when placed upon 15 the core, will not only protect the core, but will strengthen and re-inforce the entire portion of the core or shaft which is disposed between the grip and head of the club without interfering with the required flexibility 20 of the shaft and at the same time the shaft will be of the desired weight and rigidity.

To the attainment of these ends and the accomplishment of other new and useful objects as will appear, the invention consists 25 in the features of novelty in substantially the construction, combination and arrangement of the several parts, hereinafter more fully described and claimed and shown in the accompanying drawing illustrating this 30 invention, and in which:

Figure 1 is a side elevation of a golf club constructed in accordance with the principles of this invention.

Figure 2 is an enlarged detail perspective 35 view of the core.

Figure 3 is a perspective view of the casing.

Figure 4 is a longitudinal sectional view, 40 partly broken away, of a golf club shaft constructed in accordance with the principles of this invention.

Figure 5 is a view similar to Figure 4 of a modified form of the invention.

Figure 6 is a detail sectional view taken 45 on line 6-6 Figure 3.

Figure 7 is a detail sectional view taken on line 7-7 Figure 5.

While this invention has been shown and will be particularly described in connection 50 with a golf club shaft, it is to be understood that the term shaft as employed throughout the specification and claims is not to be construed as a term of limitation and as being adapted for that purpose alone, but it is

to be construed broadly as being applicable 55 to any form of shaft, staff, or for any other similar purpose and particularly to shafts subjected to impacts thereupon in directions transverse to the length thereof.

Heretofore golf club shafts have usually 60 been made of wood and some shafts have been constructed of highly tempered metal, such as steel.

While satisfactory results have been obtained with these shafts there are many objections to them.

Golf club shafts are subjected, among other things, to moisture and changing temperatures, with the result that wooden shafts or cores not only absorb moisture but they 70 will warp and split, while metal shafts will corrode and rust.

The corrosion and rust cannot be covered by painting the shaft as the paint will not 75 stick but will chip or peel off.

The corroding and rusting of the metal shafts results in considerable loss not only to the manufacturer but also to the merchant as the rusting will occur upon the shafts that are carried in stock, thereby precluding the 80 sale of the same.

It is one of the objects of the present invention to provide for the core or shaft a cover or casing of non-metallic hard material having tensile strength and which casing 85 will not only reinforce the shaft or core but possesses considerable flexibility, so as not to impair the flexibility of the shaft, at the same time, the casing will permit the finished product to possess the desired 90 weight and balance.

After the present casing is once applied, the core or shaft will be protected and no further operation, in so far as the casing is concerned is necessary, as a casing may be 95 given the desired finish before being applied, and the telescoping and wedging operation of the core and casing is all that is necessary to bind them together.

The casing and core are both formed with 100 a continuous and extended taper so that the casing will have contact with the core through the entire length of the casing.

In carrying this invention into practise 105 a tubular casing, of any suitable non-metallic material, may be employed which is adapted to be placed upon or sleeved over the core and to be fashioned to conform to

the contour of the shaft or core, the shaft or core and the casing being both continuously tapered.

The casing may, if desired, be of a length substantially co-extensive with the length of the core or may terminate short of one or both ends thereof according to the methods or means employed to fasten the head and grip of the club to the shaft.

10 In either event, however, the casing will closely fit and have a continuous contact with the core or shaft throughout the entire length of the casing.

A suitable material which has been found 15 to be efficient for this purpose is pyroxyline, but it is to be understood that it is not desired to be limited to this particular product as any other material having the properties and characteristics herein recited may 20 be employed.

A similar material or casing may be employed or placed over a shaft or core which is constructed of low grade wood and which core is either solid or tubular, enabling the 25 use of material which has heretofore been practically useless or at least unfit for use in shafts.

Referring more particularly to the drawing, the numeral 10 designates a hollow tapered core or shaft preferably produced 30 from a sheet of metal brought into form, and 11 designates a tubular casing formed from a non-metallic hard and flexible material. The casing is tapered throughout 35 its entire length and conforms to the contour of the core and the size of the casing in cross section is such that when the two are telescoped they may be bound together by a wedging operation, and at the same time they will be independent of each 40 other in that they will not be so fastened that they cannot be separated.

A head 12 is secured in any suitable manner to one end of the shaft thus formed and 45 a grip or handle 13 is applied to or formed at the other end of the shaft.

In Figure 4 the casing 11 is shown as terminating short of the end of the core or shaft 10, while in Figure 5 the casing is 50 co-extensive with the length of the core.

The casing 11 being tubular and normally tapered may be readily applied and when in place upon the core will not only protect the latter, but will not interfere with 55 the torsion or flex of the core. Furthermore the casing serves as a finish for the core, the surface of the casing itself being adapted to be finished either before or after it is applied to the core.

60 By this means it will be manifest that any desired finish may be given to the shaft as the casing may be made of any desired color or colors.

65 The tapered metallic core may be either tubular or solid and when the casing is

applied thereto the core will be protected against rust and corrosion.

With wood cores or shafts the casing will not only protect them against moisture and warping but will reinforce and brace them 70 without impairing the flexibility or the torsion of any core or shaft to which it is applied.

In shafts, such as in wood shafts, its 75 which the torsion and flexibility are usually too great, the torsion and flex may be reduced by use of this improved casing, the amount of the reduction being controlled by the degree of thickness of the casing, and at the same time the proper weight and balance 80 as well as the necessary flexibility will be maintained in the club.

By the expression "normally tapered" is meant that the casing is formed into shape 85 so that even though it is hard, it will possess considerable flexibility and is complete in itself ready to be sleeved over and wedged upon the core.

While the preferred forms of the invention have been herein shown and described, 90 it is to be understood that various changes may be made in the details of construction and in the combination and arrangement of the several parts, within the scope of 95 the claims, without departing from the spirit of this invention.

What is claimed as new is:—

1. A flexible golf club shaft embodying a tapered core, and a separate tapered tubular 100 protecting and reinforcing casing of non-metallic hard and flexible material of a length coextensive with the length of the entire portion of the core which is disposed between the grip and head of the club, the said casing telescoped over the core and wedged thereupon, the casing and core having contact throughout the entire length of the casing and being independent of each other, the said core and the interior of the casing increasing in diameter toward the 105 grip end of the club.

2. A flexible golf club shaft embodying a tapered hollow metallic core, and a separate tapered tubular protecting and reinforcing casing of non-metallic hard and flexible material of a length coextensive with the length of the entire portion of the core which is disposed between the grip and head of the club, the said casing telescoped over the core and wedged thereupon, the casing and core having contact throughout the entire length of the casing and being independent of each other, the said core and the interior of the casing increasing in diameter toward the 110 grip end of the club.

3. A flexible golf club shaft embodying a tapered core, and a separate tapered tubular protecting and reinforcing casing of pyroxyline of a length coextensive with the length of the entire portion of the core 115

which is disposed between the grip and head of the club, the said casing telescoped over the core and wedged thereupon, the casing and core having contact throughout the entire length of the casing and being independent of each other, the said core and the interior of the casing increasing in diameter toward the grip end of the club.

4. A flexible golf club shaft embodying a tapered hollow metallic core and a separate tapered tubular protecting and reinforcing casing of pyroxyline of a length coextensive with the length of the entire portion of the

core which is disposed between the grip and head of the club, the said casing telescoped over the core and wedged thereupon, the casing and core having contact throughout the entire length of the casing and being independent of each other, the said core and the interior of the casing increasing in diameter toward the grip end of the club. 15

In testimony whereof I have signed my name to this specification on this 18th day of March, A. D. 1926.

HAROLD G. BARRETT.
